FLOOR WAXER OR THE LIKE

Alvin O. Johnson, Westfield, Mass., and Alfred L. Le
Febvre, West Suffield, Conn., assignors to Stanley Home
Products, Inc., Westfield, Mass., a corporation

Filed June 8, 1966, Ser. No. 2,616

Term of patent 14 years

(Cl. D9—2)

FIG. 1.

FIG. 2.

FIG. 1 is a side elevational view of a floor waxer or the like embodying our new design, and

FIG. 2 is a top plan view thereof.

The dominant features of my design reside in the portions shown in full lines, portions of the broken lines being omitted for convenience of illustration.

The handle is shown broken away in FIGS. 1 and 2 to indicate indeterminate length.

We claim:

The ornamental design for a floor waxer or the like, as shown and described.
